UNITED STATES PATENT OFFICE

JOHN W. BOUR, OF LOS ANGELES, CALIFORNIA

CLEAR VISION DEVICE

Application filed July 24, 1929. Serial No. 380,611.

This invention appertains to transparent panes used in vehicle windshields, windows or any similar closure exposed to the elements and one of the primary objects of the invention is to provide novel means for incorporating a heating element within a transparent pane for preventing the collection of snow, rain, condensation or any moisture thereon, thereby insuring clear vision therethrough at

10 all times.

Another important object of my invention is the provision of novel transparent spacing strips interposed between a pair of transparent panes, the strips being spaced to form 15 passageways for the reception of a resistance wire used for heating purposes, the spacing strips acting as a filler and strengthening means for the panes as well as spacers for the various portions of the resistance element.

20 A further object of my invention is the provision of novel means for incorporating a burglar alarm in the heating circuit, for causing sounding of the alarm should the pane or resistance element be broken.

25 Still another object of the invention is to provide an improved device of the above character which will be durable and efficient in use, one that will be simple and easy to manufacture, and one which can be placed 30 on the market at a reasonable cost.

With these and other objects in view, the invention consists in the novel construction, arrangement and formation of parts, as will be hereinafter more specifically described, 35 claimed, and illustrated in the accompanying drawing, in which drawing:

Figure 1 is a front elevation of a windshield constructed in accordance with my invention showing parts thereof broken away and in 40 section.

Figure 2 is a vertical section through the windshield taken on the line 2—2 of Figure 1 looking in the direction of the arrows.

Figure 3 is a front elevation of a window 45 constructed in accordance with my invention with parts thereof broken away and in section and illustrating the novel means employed for connecting a burglar alarm therewith; and

50 Figure 4 is a fragmentary vertical section

taken on the line 4—4 of Figure 3 looking in the direction of the arrows.

Referring to the drawing in detail, wherein similar reference characters designate corresponding parts throughout the several views, the letter A generally indicates a vehicle windshield, which, in accordance with my invention embodies inner and outer transparent panes or plates 5 and 6 preferably formed of glass. These plates can be held 55 in any desired type of frame 7. The panes or plates 5 and 6 are held in spaced relation by longitudinally extending transparent strips 8 which can be formed of any desired material. These strips are slightly spaced 60 to provide longitudinally extending passageways 9 for a purpose which will be later described. In connection with the windshield, I employ a resistance wire 10 forming a heating element. This resistance wire is placed 65 or confined in the passageways 9 and leads from one passageway to the other as clearly shown in Figure 1 of the drawing so that the entire area of the windshield will be 70 heated thereby when a circuit is closed therethrough. The opposite terminals of the resistance wire are connected to feed and return wires 11 and 12 which can lead to a suitable source of electrical energy. These 75 wires are preferably led through an opening 80 or eyelet 13 formed in the frame 7 of the windshield.

In the manufacture of the windshield, I prefer to run straight lengths of wire in the passageways 9 and have the ends of the strips 8 staggered or alternately terminating short 85 of the opposite ends of the panes to provide end passageways 14 into which the terminals of the straight lengths of wire are led. These 90 terminals are then connected together in any desired way such as by the use of solder or the like.

It is obvious that by this construction a durable and efficient windshield is provided 95 which will prevent the collection of moisture, snow or ice thereon.

My invention is applicable for use in connection with any pane exposed to the elements and in Figure 3 I have illustrated my 100 invention incorporated with a conventional

window sash B including a frame 15. The frame 15 receives the inner and outer glass panes or plates 16 and 17 which are spaced by longitudinally extending transparent strips 18 of mica or the like. These strips are spaced relative to one another to receive resistance elements 19 in the same manner as the resistance element 10 described in Figures 1 and 2.

10. In connection with a window or other closure I can employ a burglar alarm or the like 20. The feed and return wires of the resistance element 19 are indicated by the reference characters 21 and 22 in Figure 3 and are 15 shown connected to the opposite terminals of a suitable source of electrical energy at 23. The wire 21 can have incorporated in the length thereof a suitable control switch 24.

The burglar alarm 20 may comprise a relay 20 including an electro-magnet 25 which is incorporated in the length of the wire 22. The magnet 25 normally attracts, when energized, a pivoted armature 26 and when the magnet is de-energized the armature is moved to a raised 25 position by an expansion coil spring 27. Disposed in the path of the pivoted armature is a contact 28 and the armature and the contact have attached thereto wires 29 and 30. The wire 29 has incorporated in the length 30 thereof an electric bell 31 or other suitable alarm and this wire then leads to one terminal for a suitable source of energy 32. The wire 30 leads to the other terminal of said 35 source of electrical energy. A switch 33 may also be incorporated in the length of the wire 29 for opening and closing the circuit therethrough manually.

In use of the burglar alarm, when a circuit is closed through the resistance element 40 19 the magnet 25 will be energized causing the armature 26 to move downward away from the contact 28, thus interrupting the flow of current through the alarm or signal 31. However in case of breakage of the resistance element at any point the circuit therethrough will be broken and consequently the magnet 25 will be de-energized, thus allowing raising of the armature into engagement 45 with the contact 28 by the spring 27. This will close the circuit through the signal or alarm 31 and will give the alarm.

50 Changes in details may be made without departing from the spirit or the scope of my invention.

55 I claim:

1. A transparent panel for windshields, windows and other closures comprising a pair of spaced companion transparent panes, 60 transparent strips disposed between and engaging said panes and arranged slightly in spaced relation defining passageways, a continuous resistance wire extending from one passageway to the other, and feed and return wires for said resistance wire secured 65

to the opposite terminals thereof and extending from said panels.

2. A transparent panel for windshields, windows and other closures comprising a pair of spaced companion transparent panes, 70 transparent strips disposed between and engaging said panes and arranged in slightly spaced relation defining longitudinally extending passageways, the strips having their adjacent ends terminating short of one another defining staggeredly arranged transverse passageways, and a continuous resistance wire extended from one longitudinal passageway to the other through said transverse passageways.

80 In testimony whereof I affix my signature.
JOHN W. BOUR.
